CLAIM

The ornamental design for a cooking appliance with two-dimensional applied surface graphic as shown and described.

DESCRIPTION

The file of this patent contains at least one drawing executed in color. Copies of this patent with color drawings will be provided by the Office upon request and payment of the necessary fee.

FIG. 1 is a perspective view of a cooking appliance with two-dimensional applied surface graphic according to the design; and,

FIG. 2 is a front elevation view thereof, back elevation, right and left side, and top and bottom plan views showing no claimed portion thereof.

The portions of the article shown in even broken line form no part of the claimed design.

Dash-dot-dash broken lines adjacent un-shaded areas represent bounds of the claimed design and form no part of the claimed design themselves.
